UNITED STATES PATENT OFFICE.

ALBERT J. D. OHM, OF OAK PARK, ILLINOIS, ASSIGNOR TO R. WILLIAMSON & COMPANY, OF CHICAGO, ILLINOIS, A CORPORATION OF ILLINOIS.

DESIGN FOR A LIGHTING-FIXTURE SHADE.

Application filed May 1, 1929. Serial No. 31,060. Term of patent 7 years.

To all whom it may concern:

Be it known that I, ALBERT J. D. OHM, a citizen of the United States, residing at Oak Park, in the county of Cook and State of Illinois, have invented a new, original, and ornamental Design for Lighting-Fixture Shades, of which the following is a specification, reference being had to the accompanying drawing, forming a part thereof, in which—

Fig. 1 is a front elevation,
Fig. 2 is a side elevation, and
Fig. 3 is a view of the bottom of a shade showing my new design.

I claim:

The ornamental design for a lighting fixture shade as shown.

ALBERT J. D. OHM.
